COMBINATION ATTACHMENT BOX AND BED EXTENSION FOR SEWING MACHINES

Edward W. Stanton, Cranford, N.J., assignor to The
Singer Manufacturing Company, Elizabeth, N.J., a cor-
poration of New Jersey

Filed June 30, 1960, Ser. No. 61,175

Term of patent 14 years

(Cl. D70—2)

Fig. 1

Fig. 2

Fig. 1 is a perspective view of a combination attachment box and bed extension for sewing machines showing my new design;

Fig. 2 is a perspective of the other side of the combination attachment box and bed extension shown in Fig. 1;

Fig. 3 is a top plan view;

Fig. 4 is a front elevational view;

Fig. 5 is an elevational view of one end;

Fig. 6 is an elevational rear view;

Fig. 7 is an elevational view of the other end from that shown in Fig. 5; and

Fig. 8 is a bottom plan view.

I claim:

The ornamental design for a combination attachment box and bed extension for sewing machines, substantially as shown.
